(57) **CLAIM**

The ornamental design for a Lighted American flag, as shown and described.

DESCRIPTION

FIG. 1 is a top plan view of my design for a lighted American flag, showing a lighting harness placed thereon with lights being mounted coextensive with the stars and stripes.

FIG. 2 is a left side elevational view thereof.

FIG. 3 is a front elevational view thereof.

FIG. 4 is a right side elevational view thereof.

FIG. 5 is a rear elevational view thereof; and,

FIG. 6 is a bottom plan view thereof.
